2 SHEETS—SHEET 2.

UNITED STATES PATENT OFFICE.

ALBERT E. MORGAN, OF NORTH MELBOURNE, VICTORIA, AUSTRALIA, ASSIGNOR TO JINKS AND MORGAN PROPRIETARY LIMITED, OF NORTH MELBOURNE, VICTORIA, AUSTRALIA.

LOCK.

Application filed March 16, 1921. Serial No. 452,783.

To all whom it may concern:

Be it known that I, ALBERT EDWARD MORGAN, a subject of the King of Great Britain, residing at North Melbourne, in the State of Victoria, Commonwealth of Australia, have invented new and useful Improvements in Locks (for which applications have been filed in Australia, No. 14,188, dated January 30, 1920, and No. 18,236, dated October 14, 1920), of which the following is a specification.

This invention relates to improvements in locks, and comprises strong, simple and efficient mechanism which may be readily and cheaply constructed and assembled.

Door locks in general use are of two types commercially known as rim-locks and mortise-locks. Each of these locks is normally of a distinct construction requiring for its commercial production the use of specially designed machines and tools. The lock mechanisms are usually made from cast metal, and as a consequence the parts thereof are frequently damaged or broken when subjected to any undue strain.

In the embodiment of this invention, the casings and the operative mechanism of the latch and lock-bolt are formed of stamped metal parts adapted for ready assembly in casings of either the rim-lock or mortise-lock type and the parts are strong and simple in construction and efficient in operation.

This invention resides essentially in a construction of lock mechanism comprising a spring controlled sliding latch, a yoke connected thereto having two rearwardly directed arms with lateral extension plates engaged by opposite curved surfaces on a cam member adapted to be oscillated by the handle-knob and thereby operate said latch, a key actuated lock-bolt, the shank of which has two notches and a V-shaped recess on its shank, and a pivoted spring-controlled tumbler having a dog engaging one of the said notches in the unlocked position and the other notch in the lock position, the said tumbler having outwardly projecting lugs which bear lightly against the cover plate.

Reference being had to the drawings:—

Figure 1 is a plan view of a rim-lock with the cover plate removed.

Figure 2 is a similar view of a mortise-lock.

Figure 3 is a front view of the edge-plate 55 of the mortise-lock.

Figure 4 is a view in rear end elevation, partly in section, of the mortise-lock.

Figure 5 is a view in plan, partly in section, of the bolt. 60

Figure 6 is a view in plan and Figure 7 is an edge view of the tumbler.

Figure 8 is a plan view of the rim-lock casing.

Figure 9 is a section on line *a*—*a*, and Figure 65 10 is a section on line *b*—*b* Figure 8.

Figure 11 is a view in longitudinal section of the cover plate of the rim-lock.

Figure 12 is a view in plan of a hasp.

Figure 13 is a section on line *c*—*c* Figure 70 12.

Figure 14 is a view in plan of the mortise-lock casing.

Figure 15 is a section on line *d*—*d* Figure 75 14.

Figure 16 is a front elevation of the face plate of the mortise-lock.

Figure 17 is a plan view of the cover plate of the mortise-lock.

Figure 18 illustrates a blank and Figure 80 19 is a perspective view of the yoke end member of the latch constructed from such blank.

Figure 20 is a view in perspective of the latch.

Figure 21 is a perspective view of a guide 85 for the latch shank.

Figure 22 is a view of a blank from which the latch operating cam is formed.

Figure 22^a is a view in plan, and Figure 23 is a central vertical section of the latch operating cam. 90

Figure 24 is a plan view of a blank from which a handle-knob bush is formed.

Figure 25 is a view in plan, and Figure 26 is a vertical section of the bush. 95

Figure 27 is a sectional view illustrating the bush fitted into the neck of the handle-knob.

Figure 28 is a detail end view of Figure 27. 100

Figures 8 to 17, inclusive, are drawn to a reduced scale.

In the drawings A designates a rim-lock and B a mortise-lock.

The casing 1 of the rim-lock A has a 105 flange 2 forming a seating for a cover plate 3 and an integral rim flange 4 furnished with slots 5 and 6 to receive the spring-con-

trolled latch 7 and lock-bolt 8, and with holes 9 for the reception of screws to fasten the casing in position at the edge of a door or like frame.

5 The rim flange is blanked at 10 in order that when upturned at right angles to the casing 1—as indicated by broken lines in Figure 9—to abut against the end of the casing, it conforms to the configuration of the 10 shaped side portions of the lock casing.

The lock casing is formed with holes 11 for the reception of screws to fasten the same to the face of a door, a key-slot 12, a bearing 13, apertures 14, 15, 16 and 17, and 15 an inwardly projecting stop 18 for the purposes hereinafter explained.

The cover plate 3 has an inward guide projection 19 for the latch and a hole 20 corresponding in location with the bearing 20 13 formed in the casing 1.

The lock casing with integral rim flange 4 is a metal stamping produced by the use of dies in stamping and forming operations. The formation of the bearing, the key-slot, 25 locating apertures, fixture holes, and the stop in the lock casing and the punching of the slots and fixture holes in the rim flange are performed simultaneously with the production of the casing 1 with integral rim 30 flange from a metal blank by the press operation. The cover plate 3 is likewise produced in the form of a metal stamping.

The bearing 13 receives the boss of a latch operating cam 21, while the apertures 14, 15, 35 16 and 17 function as locating points and enable a bifurcated guide 22 for the latch shank, the cover plate supporting boss 23, tumbler pivot pin 24 and a supporting guide pin 25 for the bolt to be riveted to the casing 40 in correct relative operative position.

The hasp 26 is a metal stamping having an integral securing flange 27 produced with guide slots 28 and 29 for the latch 7 and bolt 8, respectively, and with holes 30 to receive 45 attachment screws.

The lock-bolt 8 is preferably made in two parts with its shank having an enlarged outer end fitted into a recess formed in the head of the bolt and retained therein by a rivet— 50 see Figure 5.

The shank of the bolt is a metal stamping formed with notches 31 and 32 on one edge to accommodate a dog 33 of a pivoted tumbler 34. The notch 31 retains the bolt 8 in 55 its unlocked position, while the recess 32 holds said bolt in its locked position. An inverted V-shaped recess 35 is formed in the opposite edge of the bolt shank to receive the key bit and have a sliding movement 60 imparted thereto.

A lug 36 is formed at the rear of the bolt shank and is adapted to contact with the stop 18 formed on the lock casing 1 to prevent the bolt being forced too far inwardly 65 in unlocking actions.

The tumbler 34 has a recess 37 receiving one end of a spring 38 which is passed beneath a guide lug 39 on said tumbler and has its opposite end partially wound around the cover supporting boss 23.

A cam surface 40 is formed in the tumbler for the key bit whereby the turning of the key causes the tumbler to oscillate on its pivot pin 24 and elevate the dog 33 from the retaining notch 31 or 32 in the bolt shank, 70 thereby permitting the bolt 8 to be moved to its locking or unlocking position as required, whereupon the dog 33 of the tumbler engages one of said notches by the influence of the spring 38.

Lugs 41 on said tumbler project outwardly to form abutments against which the inner surface of the cover plate 3 lightly bears to maintain the tumbler in position when the lock mechanism has been assembled.

The tumbler 34 constructed in the manner hereinbefore described is a metal stamping ensuring required accuracy of construction consistent with economy in the production of the lock mechanism.

Small projections 42 are formed on the inner surface of the casing 1 and are arranged radially about the key-slot 12. The clefts of the key-bit permit freedom of key action over these projections, but by a rearrangement of the locations of said projections they form obstructions to the movement of a false key, thereby making requisite the use of special keys for different locks.

The cam 21 for actuating the spring-controlled latch 7 is a metal stamping, illustrated in detail in Figures 22, 22^a and 23, and it comprises bosses 43 connected by a bridge or distance piece 44. Each of said bosses has a square aperture 45 and one of them is provided with oppositely positioned cam pieces 46.

One of said bosses is rotatably fitted in the bearing 13 formed in the casing 1, and 110 the other boss is similarly fitted in the hole 20 provided in the cover plate 3. The apertures 45 in the bosses of the cam provide for the accommodation of a latch spindle 47 of square cross-section for the operation of 115 the latch 7.

The latch has at its inner end a yoke 48, the side members of which are formed with outwardly extending plates 49 against which the cam members 46 bear. This yoke is constructed from a stamped metal blank (illustrated in Figure 18) which is then bent to the configuration shown in Figure 19. The inner end of the latch shank is riveted to said yoke, a hole 50 being provided in the latter for this purpose. If desired, the hole 50 may be tapped and the inner end of said shank screw-threaded to provide for an adjustable connection.

The cam 21 has rotary movement im- 130

parted to it by the operation of a handle-knob 51 fitted to the latch spindle 47, causing one of the cam members 46 to force the yoke 48 rearwardly and draw the latch into the 5 casing against the tension of the spring 52.

A metal bush 53 is sprung into the neck of the handle-knob and is restrained against movement therein. This bush is constructed 10 of stamped metal as illustrated in Figure 24 and comprises two discs 54 and a bridge 55.

Square holes 56 are formed in said discs to receive the latch spindle 47. An arm 57 extending from one disc has a teat 58 which 15 engages with a recess 59 formed peripherally in the opposite disc when the bush is sprung into the neck of the handle-knob as illustrated by Figure 27.

A recess 60 formed in the edge of one of 20 said discs receives a corresponding depression 61 in the neck of the handle-knob at that point where the pinching screw 62 passes and screws into the latch spindle.

The casing 1^a of the mortise-lock B is 25 constructed from sheet metal, by stamping operations, as shown by Figures 14 to 17.

In mortise-lock constructions the guide-plate 4^a is not integral with the lock casing, but is constructed as a separate integer. Said 30 guide-plate is secured to the casing by means of projections 63 on the latter being passed through slots 64 in the former and then riveted.

The cover plate 3^a of the mortise-lock is 35 fitted to the casing 1^a by means of projections 65 engaging with recesses 66 formed in the flange 2^a of the casing. A fastening screw is then passed through a hole 67 in the cover plate and screwed into the boss 23 40 riveted to the casing.

A rim-lock is ordinarily of larger outside dimensions than a mortise-lock. Consequently the length of the shank of the latch 7 is shortened by adjustment or otherwise for 45 use with the other components of a mortise-lock. With the exception of this one alteration, the mechanism for a mortise-lock consists of the same interchangeable stamped metal parts constructed, assembled and functioning as hereinbefore described with reference to the rim-lock. The invention by 50 this means provides for accuracy of construction, efficiency in operation and economy in manufacture of locks of both types.

The key slot 12 is preferably arranged in 55 a horizontal plane (as illustrated by Figures 1 and 8), instead of being arranged verti-

cally, in order to prevent accidental displacement of the key from the lock by vibration such as is caused by the slamming 60 of a door.

What I do claim is:—

1. In a lock, the combination with a spring actuated latch of a yoke fitted to the end of the latch shank and having two arms extending rearwardly, a rotatable cam member mounted on the latch spindle and having two oppositely positioned curved surfaces in direct operative contact with two outwardly extending plates on the opposite arms of the 70 said yoke, a locking bolt having two notches and a V-shaped recess on its shank, and a spring-controlled pivoted tumbler having a dog engaging one of the said notches in the unlocked position and the other notch in 75 the locked position, the said tumbler having outwardly projecting lugs which bear lightly against the cover plate.

2. In a lock, the combination with a spring actuated latch of a yoke fitted to the end of 80 the latch shank and having two arms extending rearwardly, a rotatable cam member mounted on the latch spindle and having two oppositely positioned curved surfaces in direct operative contact with two outwardly 85 extending plates on the opposite arms of the said yoke, said cam member comprising two bosses spaced apart by a bridge which is stamped integrally with the said bosses, one of said bosses being extended to form a cam. 90

3. In a lock, the combination with a spring actuated latch of a yoke fitted to the end of the latch shank and having two arms extending rearwardly, a rotatable cam member mounted on the latch spindle and having 95 two oppositely positioned curved surfaces in direct operative contact with two outwardly extending plates on the opposite arms of the said yoke, a handle-knob operating said spindle, a bush for the latch spindle 100 sprung into the neck of said knob, said bush consisting of a metal stamping formed from one strip of sheet metal and comprising two discs, a bridge, an arm extending from one disc, a teat on said arm, 105 and a recess in the opposite disc engaging said teat.

In testimony whereof I affix my signature in presence of two witnesses.

ALBERT E. MORGAN,

Witnesses:

JAMES H. ANDERSON,
ANDREW W. SMITH.
